(74) *Attorney, Agent, or Firm* — Barry Choobin; Patent 360

(57) **CLAIM**

The ornamental design for a combined spray bottle with a storage compartment, as shown and described.

DESCRIPTION

FIG. 1 is a perspective view of a combined spray bottle with a storage compartment, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof, in which the storage compartment is attached.

The dot-dash broken lines in the figures show boundaries that form no part of the claimed design.

The broken lines depict portions of the article that form no part of the claimed design.

1 Claim, 7 Drawing Sheets
